UNITED STATES PATENT OFFICE.

ROLLIN C. LEWIS, OF STAMFORD, CONNECTICUT, ASSIGNOR TO THE YALE & TOWNE MANUFACTURING COMPANY, OF STAMFORD, CONNECTICUT.

DIAL LOCK.

1,403,793.

Specification of Letters Patent. Patented Jan. 17, 1922.

Application filed May 27, 1921. Serial No. 472,970.

To all whom it may concern:

Be it known that I, ROLLIN C. LEWIS, a citizen of the United States and a resident of Stamford, in the county of Fairfield and 5 State of Connecticut, have invented certain new and useful Improvements in Dial Locks; and I do hereby declare the following to be a full, clear, and exact description of the invention, such as will enable others 10 skilled in the art to which it appertains to make and use the same.

My improvement relates to an improvement in dial locks the object being to provide improved means for locking the cover 15 to the lock case and for automatically locking the curb against accidental displacement when the cover is removed from the case, and it consists in the parts and combination of parts as will be more fully explained and 20 pointed out in the claims.

In the accompanying drawings; Figure 1 is a view in elevation of the lock, the cover being removed, the locking lug on the cover being shown in dotted lines; Figure 2 is a 25 view in side elevation partly in section showing the cover in place; Figure 3 is a view in elevation of a part of one end of the lock case showing the dove-tailed slot to receive a similarly shaped tenon on the 30 lock case for holding the cover through the lug 18 and part of the curb.

5 represents the lock case, 6 the bolt and 7 the fence for actuating the bolt.

The tumblers 8 are mounted on a sleeve 35 (not shown) carried by the curb 9 and are turned or rotated by the dial knob 10, in the usual and well known manner.

The lock case 5 is provided at its opposite ends with the dovetailed slots 11 to receive 40 similarly shaped tenons 12 formed integral with the cover 13, and the latter is provided at its rear end, or its end adjacent the curb and tumblers with an integral lug 14, which latter rests with its front edge adjacent the 45 peripheries or rims of the tumblers as shown in Figure 2, so that before the cover can be slid endwise on the case to disengage the tenons 12 on the cover from the slots 11 in the ends of the lock case 5, the tumblers must be set upon the proper combination 50 to bring the gatings therein into alinement with said lug. After the tumblers have been so set or manipulated, and the screw 17 securing the cover in place 55 removed, the cover may be moved or slid

forwardly to disengage the tenons thereon from the slots 11, and removed.

The curb 9, which as before explained carries the tumblers in the usual and well known manner, is held in place within the lock by a plurality (four in the present instance) of undercut lugs 18 and 18^a formed integral with the lock case, the curb 9 being provided with peripheral notches 19 so located with relation to the lugs, that when 60 the notches are in alinement with the lugs, the curb with its assembled tumblers thereon can be placed in position or removed from the lock, and when inserted or partly rotated, the periphery or rim of the curb 65 will be carried under the shoulders 21 on the lugs and be held thereby against outward movement or displacement, the gating 20 in the curb cooperating with one of said lugs and performing the function of a 70 notch 19, thus providing a notch for each holding lug.

The lug 18 is made hollow or recessed for the reception of the plunger 22, and the latter is provided with a stem 23. This stem 80 passes through the bushing 24, which closes the recess in lug 18 and limits the outward movement of the plunger 22. The plunger is forced outwardly by the spring 25 which normally holds the free end of the stem of 85 the plunger in contact with the inner face of the cover, but when the cover is removed the plunger is then free to be forced outwardly into the plane of the curb 9 and enter a notch 26 in said curb and thus lock 90 the latter against accidental turning movement, and consequent displacement when the cover of the lock is not in place, the recess in the lug 18 being open in the plane 95 of the curb and immediately under shoulder 21, to permit the plunger to enter notch 26. When the plunger is within notch 26 in the curb the latter will be locked against turning on releasing movement, hence in order to remove the curb and its nested tumblers, 100 the plunger must be forced inwardly by pressure against the free end of the stem thereof so as to carry the plunger out of the plane of the curb. When the cover is in place, the plunger is as before explained 105 held out of contact with the curb by said cover.

Figure 1 shows the tumblers set upon the proper combination for the entrance of the lug 14 into the gatings in the tumblers, thus 110

permitting the cover to be moved or slid forwardly to carry the tenons 12 out of the dovetailed recesses and when the tenons are clear of the dovetailed recesses or mortises, 5 the cover will be free to be removed. As the cover is removed, the plunger 22 will be forced outwardly by the spring and into the notch 26 in the rim of the curb and prevents any accidental rotary displacement 10 of the curb and its associated tumblers. To remove the curb and tumblers, the plunger 22 is forced inwardly until it is out of contact with the curb, thus permitting the latter to be turned to bring the notches 19 therein, 15 into alignment with the shoulders 12 on the lugs 18 and 18^a, after which it and its connected tumblers may be lifted from the lock case 5.

It is evident that many slight changes 20 might be resorted to in the relative arrangement of parts shown and described without departing from the spirit and scope of my invention hence I would have it understood that I do not wish to confine myself to the 25 exact construction and arrangement of parts shown and described but,

Having fully described my invention what I claim as new and desire to secure by Letters-Patent, is:—

30 1. The combination of a lock case having a series of undercut lugs, a curb having a notched periphery whereby it may be entered between the lugs and locked to the latter by turning the curb, disk tumblers 35 carried by the curb, each tumbler having a gating, and a cover for the case having an inwardly projecting lug adapted to engage the peripheries of the tumblers and prevent the cover from being moved in a direction 40 to detach it from the lock case except when the gatings in the tumblers are in line with the inwardly projecting lug on the cover.

2. The combination of a lock case having

a series of under cut lugs, a curb having a notched periphery whereby it may be entered between the lugs and locked by turning it to engage the shoulders on the lugs, 45 a spring pressed plunger adapted to engage the curb for locking it against turning movement, and a cover adapted when in 50 place to bear against said plunger and hold it out of contact with the curb.

3. The combination of a lock case having a series of under cut lugs, a curb having a notched periphery whereby it may be entered between said lugs and locked by turning it to engage the shoulders formed by undercutting the lugs, a spring actuated plunger adapted to engage the rim of the curb and prevent the latter from turning, 60 the said plunger being provided with a stem, and a cover for the case, the said cover adapted when in place to engage the stem of the plunger and hold the latter out of contact with the curb. 65

4. The combination of a lock case having a series of undercut lugs, a curb having a notched periphery whereby it may be entered between the lugs and locked by turning it to engage the shoulders formed by 70 undercutting the lugs, a spring pressed plunger mounted in one of said lugs and adapted to enter a notch in the periphery of the curb for locking the latter against turning movement, the said plunger having 75 a stem, and a cover adapted when in position on the lock case to engage said stem and hold the plunger inwardly and out of contact with the curb.

In testimony whereof, I have signed this 80 specification in the presence of two subscribing witnesses.

ROLLIN C. LEWIS.
